UNITED STATES PATENT OFFICE

2,519,181

RECORD SHEET ASSEMBLY

Stanley B. Freiberg, Cincinnati, Ohio

Application May 18, 1945, Serial No. 594,515

1 Claim. (Cl. 129—16.5)

1

This invention relates to improvements in a visible margin file of the general character disclosed in my pending application for Patent Serial No. 570,652, filed December 30, 1944 now abandoned, and in my issued United States Patent No. 2,303,074, dated November 24, 1942, both relating to extensible files.

An object of the invention is to provide in a file assembly of the extensible type above referred to, an improved form of carrier for data sheets or inserts which may be interchanged or substituted with ease and dispatch whenever changes in the records are required.

Another object is to provide means whereby changes or substitutions in the record data may be quickly and conveniently effected, without resorting to erasures, or to the rewriting of associated data that requires no change or alteration.

Another object is to produce a convenient, inexpensive, and durable assembly of carrier and insert elements, for the purposes outlined above.

The foregoing and other objects are attained by the means described herein and illustrated in the accompanying drawings, in which:

Fig. 1 is a fragmental elevational view of the visible margin file provided with a rear and a front cover, the latter being shown in detail and with a small portion broken away.

Fig. 2 is a top view of the Fig. 1 file assembly, showing the carriers interposed between the covers.

Fig. 3 is an end view of the Fig. 1 assembly, looking from right to left.

Fig. 4 is an enlarged cross-sectional view taken on line 4—4 of Fig. 1, and showing the front cover and one carrier element.

Fig. 5 is a plan view of a complete carrier with data sheets or inserts applied thereto.

Fig. 6 is a detail view showing one of the data sheets or inserts.

Fig. 7 is an edge view of an assembly of data sheets or inserts, showing how they may be fanned out or pivotally displaced relatively in order to expose data or information applied thereto at locations other than upon the margins.

As in the patented structure, the assembly here disclosed includes a series of links 22 for pivotally connecting together a plurality of carriers 20 having free or unconnected end portions 21. The carriers may be of any form, shape, or size, although as shown herein they are rectangular and of a length exceeding their height. The head ends of the carriers are provided with means

to cooperate with the links in effecting the necessary detachable connections for assembling the carriers into a unit.

In the preferred form of the invention, the head end of each carrier is perforated to provide a series of aligned elongated and relatively narrow slots or slits 24. The number of slots or slits 24 formed in the carriers is immaterial, but should be sufficient in number and their spacing should be such that adequate anchorage is provided for interlock lugs or fingers such as 25, 26, 27, 28 of a link 22, when inserted in the slots.

In addition to the slots or slits 24, the carriers are perforated to provide a plurality of relatively wide but shorter apertures or slots 29, which, for purpose of differentiation from the interlock slits 24, may be termed connector apertures. All of the slots or apertures 24 and 29 extend through the carrier, and its head flap 23, which flap is preferably integral with the carrier and substantially coextensive with the head end thereof. The flap may be adhesively secured flatwise to the head of the carrier.

Each link such as 22 is provided with connector fingers or lugs 30 adapted to enter the connector apertures 29 for connecting or attaching one carrier-and-link unit to another similar unit, as explained in the aforesaid Patent 2,303,074. An infinite number of such units may be joined together by means of the links, to provide a compact file with all the carriers and links lying substantially flatwise against one another. The carrier and the links may be of writing paper thickness, or of a thickness approximating that of an ordinary business card. In fact, both may be of paper or light paper board construction.

The complete file is illustrated by Figs. 2 and 3, with the links and carriers under stress to separate them laterally in order to make a clear disclosure of the assembly. Normally the links and carriers of Fig. 3, for example, would all assume substantially vertical positions and would be compacted in flatwise condition to produce a file approximating in thickness the combined thickness of the carriers, links, and covers constituting the assembly. It may here be noted that by grasping the Fig. 3 assembly by its front cover head 37, and permitting gravity to act upon the carriers and the rear cover, successive carriers will hang at progressively lower elevations to dispose the carriers in échelon arrangement and thereby expose the lower margins of all the carriers to view. The width of margin exposed will be governed by the height of the slots or apertures 29,

in which the necks 34 of connector lugs or fingers 30 may shift vertically.

From the region of the neck 34, the connector lugs or fingers are turned in opposite directions to extend beyond the limits of apertures 29. The terminal ends 31 and 32 of said lugs or fingers overlap the carriers adjacent to the apertures, and serve normally to preclude separation of the link and carrier. Separation may be effected, however, by bowing the link or the carrier, or both, to withdraw the lugs or fingers from the apertures. By this means, any carrier-link unit may be removed from the assembly, or others may be added thereto.

The notch 36 between each lug or finger and the adjacent edge of the link is slightly wider than the thickness of the carrier at the apertures 29, so that the link may slide along the carrier toward and from the lower free edge 21 without binding. The construction permits also a swinging of the link bodily relative to the carrier, through an arc of approximately 180 degrees, about a horizontal axis which includes the notches 36. Said axis is shiftable toward and from the free edge of the carrier, within the limits imposed by the height of apertures 29.

The aforesaid swinging movement of the links through an arc approximating 180 degrees, will necessarily result in a condition such as Fig. 3 illustrates, wherein the interlock lugs 25 to 28, and the attachment lugs 30—30, stand out substantially at right angles to the carriers. In the outstanding condition, the lugs are obviously subject to damage, and even in the normal condition of flatwise relationship to the carriers, they may become caught upon other carriers, drawer partitions, or the like and suffer damage or distortion. To avoid such mishaps, special front and rear covers are provided for the file of carriers, designed to fully protect the lugs.

The covers are illustrated by Figs. 1 to 4. Front cover 38 is shown in elevation upon Fig. 1, and will be seen to comprise a flat sheet of paper, fiber, light cardboard or the like, having a head 31 provided by folding the sheet upon itself at the top. The depending folded-down portion, indicated at 39, constitutes a link anchor flap. Perforations 40 formed in the flap are properly spaced to receive the lugs or fingers 25, 26, 27, 28, in substantially the same manner as said lugs are received by the interlock slots or slits of the carriers. That is, the perforations 40 are spaced apart a distance somewhat greater than the distance between adjacent lugs, so that flexing or bowing of the flap is necessary to attach and detach the cover relative to the lugs.

The flap 39 may also have a pair of apertures 41 formed therein at a lower elevation than apertures 40, to receive attachment lugs such as 30 in the event that the cover 38 is to be used as a rear cover. The apertures 41 are spaced apart approximately the same distance as the attachment apertures 29 in the carrier. A slit 42 in the flap above each aperture 41, is adapted to receive a tab 43 on the face of the cover to lock the flap 39 to the cover portion 38 adjacent to the series of apertures 40.

The cover 38 is pierced or cut away over an area which includes the apertures 40 and 41, so as to provide a resilient pad 44 which overlies all said apertures and any link lugs that may extend through them. Thus, at the left side of Fig. 1, resilient pad 44 covers the lugs 25 and 26 of the link attached to the first carrier 20, next to the flap 39, (Fig. 3). The pad preferably is integral

with the cover at 45. However, it might be applied as a separate part if desired. The function of pads 44 is to furnish a protective overlay for the lugs of the links which attach to the anchor flaps, and to relieve pressure of the cover upon the lugs as the links 22 pivot within the openings 40 or 41, (Fig. 4). The pads serve also as resilient means urging the lugs toward parallelism with the flap whenever the lugs are disposed at less than a right angle to the flap. When the lugs are not outwardly extended, the pads rest in the plane of cover 38. In all positions of the pads, the lugs which they overlie are fully protected against injury such as might occur if they became caught or entangled with extraneous objects.

The back or rear cover 46 may be identical with front cover 38 if desired, although as herein illustrated the front cover is slightly higher and extended farther above the heads of the carriers. It is preferred to increase the height of the front cover sufficiently to enable one or more windows 47 to be formed therein by removal of material from the head portion, leaving the anchor flap solid behind the window or windows in order to properly support an identifying card or strip 48, as plainly shown in Fig. 4. The shank 49 of tab 43 may serve as a support for the lower edge of strip 48, as the strip rests within the window channel between the cover and its down-turned anchor flap 39.

In Fig. 1, the character 50 indicates a finger grip or hanger formed by removal of a part-circular section from both the cover and the flap. The aperture 50 may be used as an eye, if desired, in the event that the file is to be suspended from a hook or other support while the margins of its carriers are exposed in echelon fashion beneath the lower edge 51 of the front cover. In such event, the lower edge 52 of the rear cover 46 will hang slightly lower than the lowest carrier of the assembly, or that carrier which is next to the rear cover. The carriers, thusly disposed in echelon fashion, will substantially flatly contact each other and the series of links will be substantially parallel to the carriers. The pads 44, of course, will then be coplanar with the covers of which they are a part, and will overlie the link lugs in protective fashion. The head 53 of the rear cover 46 need not include windows, although it might preferably include an aperture like 50 (Fig. 1) to facilitate handling the file, or to enable suspension thereof by the rear cover, to expose marginal portions of the backs of the carriers.

Referring more particularly to the carrier, Fig. 5 shows the front thereof and upon which is mounted a series of interlocked and overlapping record sheets 55, 56, 57, 58 and 59. The record sheets may be of the same paper stock as the carrier if desired, although correspondence in this regard is not essential. For an understanding as to the shape of each record sheet, attention is directed to Fig. 6. All of the record sheets correspond to the illustration of Fig. 6, except the larger one indicated at 55, which is distinguished from the others by reason of the fact that it is of greater vertical height. It should clearly be understood that all of the record sheets might under certain requirements of recording, be of uniform vertical height, to correspond with Fig. 6, and any number thereof may be applied to the carrier within the limit of its capacity.

The lower edge 60 of each record sheet is provided with two or more hook shaped tabs 61 and 62 formed integrally with the sheet at the neck

63. Terminal ends 64 of the tabs extend in opposite directions lengthwise of the lower edge 60 of the record sheet, from which said free ends are separated by means of the slits 65. Directly above the neck of each tab, the body of the record sheet is slitted as at 66 and 67, for reception of the hooked end of a subjacent record sheet, as illustrated by Fig. 5. The subjacent sheet is the sheet 58, which underlies the sheet 59 except for the exposed upper marginal portion thereof. The vertical distance between slits 66-67 and the lower edge 60 of any record sheet, determines the visible margin exposable upon a subjacent record sheet attached thereto through the agency of the slits and the hook-shaped tabs. It will be noted that the terminal end 68 of each slit 66 or 67, where the neck of a tab hook of another record sheet engages, is located directly above the base of the slit 65 of its corresponding hook-shaped tab. In a direction horizontal from the terminal end 68, the slits 66 and 67 may extend a reasonable distance such as will enable the introduction therein, of the hook elements carried by an adjacent record sheet. The hooks of one sheet are to be disengaged from the slits of the next sheet by slightly bending or distorting one or both of the sheets, in the middle portion thereof. By the same procedure, any number of successive record sheets may be hooked together in overlapping relationship, to expose an upper margin of each sheet, as illustrated by Fig. 5. The relationship of successive record sheets to one another is such that they may be swung about their connections with a hinging movement, as suggested by Fig. 7, thereby to expose to view the bodies of all the sheets, as well as the margins thereof, for the reception of data to be printed or written thereon. Such disposition of the record sheets, of course, is possible only when the record sheet assembly is removed from the carrier which ordinarily supports the record sheets.

The carrier, indicated generally by the character 20, may be a single flat sheet of suitable paper, the upper end of which is shortened somewhat in length to furnish the head flap 23, this flap being folded down and adhesively secured to the forward face of the carrier sheet. The connector apertures 29 and the interlocking slits 24 previously referred to herein, extend through both the body and the head flap of the carrier. The ends of the head flap are indicated at 69, and are located at a distance from the side edges 70 and 71 of the carrier. The lower edge 21 of the carrier is a raw edge, that is, no flap is present along said lower edge.

In order to provide side pockets at the face of the carrier, for accommodating the end portions 72 and 73 of all the record sheets, the side margins of the carrier are folded along the edges 70 and 71, to overlie a limited area of uniform width vertically adjacent to the side edges of the carrier. The fold members which overlie the forward face of the carrier, are indicated at 74 and 75. Near the upper ends of the fold members, the carrier body is slitted horizontally, from approximately the location 76 to the adjacent side edge of the carrier and through this slit the upper end of the fold member is passed to the rear of the carrier body, where it is adhesively attached thereto. The broken line 77 indicates the upper end of the fold member, which is stuck to the rear face of the carrier body. Said upper end follows the contour of the corner of the carrier body, which may be rounded as herein dis-

closed. In initially forming the fold member, it is separated from the body of the carrier along the full length of the corner, from the line 77 to the outer end 78 of the horizontal slit 76. Where the fold member 74 passes to the rear of the carrier through the slit 76, the upper end of the record sheet pocket terminates, as will be understood.

The lower terminal end 79 of fold member 74 has integrally formed thereon a lower anchor tab 80, which extends through a horizontal slit 81 in the carrier body, from front to rear, said tab 80 being turned upwardly at the rear of the carrier and pasted against the rear face thereof by means of a suitable adhesive. The lower extremity of the record sheet pocket of the carrier, is thereby established where the tab 80 passes through the carrier at 81. The lower extremity of said pocket is located vertically above the lower edge 21 of the carrier, so that the hooked tabs 61 and 62 of the lowermost record sheet will have the protection of the backing effect furnished by the lower marginal portion of the carrier.

A carrier constructed as above explained has the advantage of extreme simplicity, substantial durability, and maximum supporting ability for hingedly connected record sheets. Moreover, such carrier can be manufactured at minimum cost, with the use of simple machinery. The side pockets formed by the side fold members 74 and 75, serve to tightly hold the vertical end portions of the record sheets, and since the fold members are integral with the carrier body, substantial resistance to bending of the carrier in a horizontal direction is effectively induced. The manner in which the end anchorage portions of the fold members is effected, insures a sturdy and durable construction having a long, useful period of service.

It is to be understood that record sheets of any type other than that illustrated herein can be accommodated by the carrier described. For example, a rectangular, plain record sheet might be applied to the carrier and held in place thereon by means of the fold members 74 and 75. Should it be desired to omit the margin along the lower edge 21 of the carrier body, the fold members 74 and 75 might be extended downwardly so as to meet the carrier edge 21, thereby placing the lower terminus of the side pocket at the same elevation as the edge 21.

What is claimed is:

A record assembly which consists essentially of a plurality of record sheets arranged in echelon formation to expose a writing area along a longitudinal edge of each sheet and each sheet having an opposed longitudinal hinge edge, a pair of hook-shaped tabs along the hinge edge of each sheet and in substantial parallelism therewith, the tabs having free ends extending outwardly beyond the hinge edge of the sheet and being separated partially from said edge by short slits extending lengthwise along said hinge edge, leaving a neck connecting each tab to the hinge edge, free ends of the tabs projecting in opposite directions lengthwise of the sheet, each sheet being slitted opposite and spaced from each tab neck a distance approximating the width of the writing area, the slits of each sheet being substantially straight and running substantially parallel to the hinge edge, each slit being of a sufficient length to accommodate therein one of the tab necks of an adjacent sheet, the sheets being arranged with the hinge edges of the sheets parallel and with the tabs and slits of adjacent

sheets in engagement to removably attach the sheets together, the sheets being adapted to swing about the hinge edges, all sheets being adapted to swing in the same direction to permit the assembly to pass about a roller.
